Primary Examiner—Catherine Tuttle*(74) Attorney, Agent, or Firm*—Michael J Wallace, Jr.(57) **CLAIM**

The ornamental design for a dispenser, as shown and described.

DESCRIPTION

FIG. 1 is a perspective view of the dispenser showing our new design.

FIG. 2 is a front elevation view thereof.

FIG. 3 is a rear elevation view thereof.

FIG. 4 is a left side elevation view thereof.

FIG. 5 is a right side elevation thereof.

FIG. 6 is a top plan view thereof; and,

FIG. 7 is a bottom plan view thereof.

The broken lines in FIG. 7 are included for the purpose of illustrating a portion of the dispenser that forms no part of the claimed design.

1 Claim, 7 Drawing Sheets
